CLAIM

The ornamental design for a specimen cup support, as shown and described.

DESCRIPTION

FIG. 1 is a top perspective view of a specimen cup support. FIG. 2 is a bottom perspective view of the specimen cup support of FIG. 1.

FIG. 3 is a top plan view of the specimen cup support of FIG. 1.

FIG. 4 is a bottom plan view of the specimen cup support of FIG. 1.

FIG. 5 is a side elevation view of the specimen cup support of FIG. 1.

FIG. 6 is another side elevation view of the specimen cup support of FIG. 1.

FIG. 7 is a rear elevation view of the specimen cup support of FIG. 1; and,

FIG. 8 is a front elevation view of the specimen cup support of FIG. 1.

The dash-dot-dot-dash broken line in the figures illustrates the boundary of the claimed invention and forms no part of the claimed design. The appearance of the specimen cup support within the boundary line forms no part of the claimed design.

1 Claim, 3 Drawing Sheets
